United States Patent Office

Des. 187,939
Patented May 17, 1960

187,939

PLATE OR SIMILAR ARTICLE

Leonard Blackman, New York, N.Y.

Application November 2, 1959, Serial No. 58,176

Term of patent 3½ years

(Cl. D44—15)

The figure is a plan view of a plate or similar article of conventional configuration, showing my new design.

I claim:

The ornamental design for a plate or similar article, as shown and described.
